T. O. BUSSLER,
SCRUBBING BRUSH HOLDER,
APPLICATION FILED APR. 6, 1921.

1,385,902.

Patented July 26, 1921.

UNITED STATES PATENT OFFICE.

THOMAS O. BUSSLER, OF WHEELERSBURG, OHIO, ASSIGNOR OF ONE-HALF TO DAVID BUSSLER, OF WHEELERSBURG, OHIO.

SCRUBBING-BRUSH HOLDER.

1,385,902.

Specification of Letters Patent. Patented July 26, 1921.

Application filed April 6, 1921. Serial No. 459,036.

To all whom it may concern:

Be it known that I, THOMAS O. BUSSLER, of Wheelersburg, in the county of Scioto and State of Ohio, have invented certain new and useful Improvements in Scrubbing-Brush Holders; and I do hereby declare the following to be a full, clear, and exact description of the invention, such as will enable others skilled in the art to which it

10 appertains to make and use the same.

In Letters Patent No. 1,320,311 issued October 28, 1919, on my application, I showed a detachable brush holder having as its primary feature the readiness with which

15 the holding device may be attached to and removed from a brush.

In the present instance I have the same object in view but I provide the added feature of rendering the holder adjustable to

20 brushes of varying sizes.

Figure 1 is a side elevation and Fig. 2 a top view.

The brush 1 is of the ordinary commercial type, having a flanged head 2. The invention relates to the means by which the brush is held on an elongated handle 3 so that the user may apply the brush to points beyond the reach of the hand.

I have shown the handle provided with a 30 pair of forwardly diverging arms 4 and spaced apart at their extremities about two inches. These arms may be attached to the sides of the handle, as by screws 5. They 35 preferably consist of flat strips of metal twisted and bent near their free ends to form downward extending hooks 6 to receive the flanged head of the brush and present flat surfaces against the flanges. The arms are maintained in the correct relationship by being riveted to an intermediate block 7.

The arms 4, intermediate the hooks 6 and the handle, constitute a rigid shank portion. In this portion I form the arms with alining 45 holes 8. On a pin 9 which may be passed through any two opposite holes is fulcrumed a lever 10 whose function is to co-act with the hooks 6 to hold the brush. This lever is shown consisting of a flat bar twisted and 50 bent near each end, the lower end 12 to en-

gage the brush head and the upper end 13 to constitute a finger hold.

To maintain the lower end 12 of the lever normally in brush-engaging position, that is, toward the hooks 6, I provide a coil 55 spring 14 secured at one end to the lever above the fulcrum point and anchored at its other end to the shank, preferably to a block 15 rigidly mounted between the arms.

Obviously the article may be cheaply 60 manufactured. In use the operator simply grasps the finger hold 13 and turns the lever on its fulcrum against the tension of spring 14, in order to insert or remove the brush. Many sizes and widths of brushes are now 65 being used and the usual types of detachable holders are not adapted to them all. By my invention I provide a wide range of adjustment by means of the holes 8 in any alining pair of which the pin 9 on which the lever 70 10 is fulcrumed may be mounted.

I claim as my invention:

1. In a brush holder, a handle, a pair of arms projecting from said handle and terminating in downward extending hooks, a 75 vertically disposed lever fulcrumed between said arms and having a downward projecting hooked extremity, and a spring anchored at one end to a fixed portion of the device and secured at the other end to said 80 lever above its fulcrum point.

2. In a brush holder, a handle, a pair of arms projecting from said handle and terminating in downward extending hooks, said arms having a series of alining holes, 85 a pin passed through any corresponding pair of said holes, a vertically disposed lever fulcrumed on said pin and having a downward projecting hooked extremity, and a spring anchored at one end to a fixed portion 90 of the device and secured at the other end to said lever above its fulcrum point.

3. In a brush holder, a handle, a pair of spaced apart arms projecting from said handle and constituting a rigid shank, said arms 95 comprising flat metallic plates twisted and bent near their free ends to form downward extending hooks, a block between said arms to which the latter are secured to maintain their spaced relationship, said arms having 100

a series of alining holes, a pin passed through any alining pair of holes, a vertically disposed lever fulcrumed on said pin and comprising a flat metal bar having its upper extremity twisted and bent to form a finger hold and its lower extremity twisted and bent to form a hook, and a spring an-

chored at one end to said shank and secured at the other end to said lever above its fulcrum point.

In testimony whereof I have signed this specification.

THOMAS O. BUSSLER.
